UNITED STATES PATENT OFFICE

JOHN O. MCKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS

COP CONE HOLDER FOR CREELS

Application filed October 4, 1928. Serial No. 310,261.

The object of my invention is to provide a very simple and effective device whereby a downwardly inclined cop cone may be held by friction on its supporting spindle in such a manner that the cone can be rotated on its spindle and may be readily slipped on and off the spindle.

My improved device comprises, broadly, an expansion spring rotatively mounted on the spindle and frictionally engaging the interior walls of the cop cone. My invention more specifically comprises a spindle having its outer portion of smaller diameter than its inner portion, a screw engaging the outer end of the spindle being provided for rotatively supporting the spring, the spring having a central portion mounted on the screw and provided with rearwardly extended bowed arms arranged to frictionally engage the interior walls of the cop cone.

Practical embodiments of my invention are represented in the accompanying drawings, in which

Fig. 1 represents one embodiment of my invention, the cop cone being shown in longitudinal central section and the holder in side elevation.

Fig. 2 represents a cross section taken in the plane of the line II—II of Fig. 1, looking in the direction of the arrows.

Fig. 3 represents a cross section taken in the plane of the line III—III of Fig. 1, looking in the direction of the arrows.

Fig. 4 represents a detail view showing another embodiment of my invention in which the annular groove in the interior walls of the cop cone is omitted.

Fig. 5 represents one form of the spring in perspective.

40 The cop cone denoted by 1 may be made of wood or other suitable material and of the desired shape, the bore of which cone is denoted by 2.

The stationary spindle which is adapted to enter the bore of the cop cone is herein shown as having an inner portion 3 of one diameter, an outer portion 4 of a smaller diameter and an intermediate tapered portion 5. The inner portion of the spindle is adapted to loosely fit within the bore 2 of the cop cone 1.

An expansion spring is rotatably mounted at the outer end of the spindle, which spring is herein shown as comprising a central portion 6 and a pair of rearwardly extended arms 7, 8, which arms are preferably bowed to facilitate the slipping on and off of the cop cone.

The means which I have shown for rotatably mounting the spring at the outer end of the spindle comprises a screw threaded into the end of the spindle, said screw being provided with an enlarged shank portion 9 adjacent its head 10, on which enlarged shank portion the central portion 6 of the expansion spring is mounted.

In the form shown in Fig. 1, the bore 2 of the cop cone is provided with an annular groove 11 at the point where the bowed arms of the spring engage the walls of the bore for assisting the arms in holding the cop cone 70 on the spindle. In Fig. 4 this groove is omitted and the frictional engagement of the arms with the walls of the bore of the cop cone is intended to be sufficient to hold the cop cone 75 on the spindle. It will be seen from the above description that I have provided a very simple and effective means for frictionally holding the cop cone on its spindle, the spring for accomplishing this purpose being intended to rotate with the cop cone on the 80 spindle as well as holding the cop cone in position on the said spindle.

It is evident that various changes may be resorted to in the construction, form and arrangement of the several parts without departing from the spirit and scope of my invention, hence, I do not intend to be limited to the particular embodiments herein shown and described, but

What I claim is:

1. A cop cone holder comprising a spindle, a screw engaging the outer end of the spindle and an expansion spring rotatably mounted on the screw and arranged to frictionally engage the interior walls of the cone.

2. A cop cone holder comprising a spindle having its outer portion of lesser diameter than its inner portion, an expansion spring having a central portion rotatably mounted at the outer end of the spindle and also hav-

ing rearwardly extended arms for frictionally engaging the interior walls of the cone and a screw engaging the outer end of the spindle and forming a mounting for the spring.

- 5 3. A cop cone holder comprising a spindle having its outer portion of lesser diameter than its inner portion, an expansion spring having a central portion rotatably mounted at the outer end of the spindle and also having rearwardly extended bowed arms for frictionally engaging the interior walls of the cone and a screw engaging the outer end of the spindle and forming a mounting for the spring.

10 15 In testimony, that I claim the foregoing as my invention, I have signed my name this 2nd day of Oct. 1928.

JOHN O. McKEAN.
